(57) **CLAIM**

The ornamental design for a fluid flow channel applied to roof drainage, as shown and described.

DESCRIPTION

FIG. 1 is an upward looking perspective view of a fluid flow channel applied to roof drainage;

FIG. 2 is a profile view thereof; and,

FIG. 3 is a profile view of an alternate embodiment substantially similar to the embodiment disclosed in FIGS. 1 and 2, the difference being the change in contours as illustrated in FIG. 3.

The nature of the article is to convey rainwater runoff from a roof structure and the intended use is the same.
